UNITED STATES PATENT OFFICE.

CHARLES J. VAUGHN, OF CLEVELAND, OHIO.

GARBAGE-CAN.

SPECIFICATION forming part of Letters Patent No. 634,677, dated October 10, 1899.

Application filed August 31, 1898. Serial No. 689,923. (No model.)

To all whom it may concern:

Be it known that I, CHARLES J. VAUGHN, residing at Cleveland, county of Cuyahoga, and State of Ohio, have invented certain new and useful Improvements in Garbage-Cans; and I do hereby declare the following to be a full, clear, and exact description of the invention, such as will enable others skilled in the art to which it pertains to make and use the same.

My invention relates to cans more especially intended to hold garbage or like odorous substances.

My invention consists in the peculiar construction of said can, whereby the same when covered is sealed.

My invention also consists in other details of construction to be fully set forth and claimed.

In the accompanying drawings, Figure I is a view in perspective of a receptacle or can constructed according to my invention. In this figure the cover is shown in section to more clearly illustrate the details of construction. Fig. II is a sectional view illustrating more clearly the liquid seal. Fig. III is a sectional view showing the water-trough in position supported by a cleat. Fig. IV is a sectional view of a central portion of a cover, illustrating my preferred construction of relief or air-escape valve.

Heretofore and before my invention various constructions of this class of cans have been devised with the object in view of so sealing the cover to the body as to prevent the escape of obnoxious or injurious gases or odors. This is essential, inasmuch as on account of the use to which these cans are put it is necessary that the covers form an air-tight connection with the body of the can. It is also essential that the cover of the can may be quickly and easily removed from the body and easily and quickly replaced thereon.

It is therefore the object of my invention to provide a construction which embodies the above features and which shall be economical to construct, while at the same time shall be effective in operation.

The body A of the can may be of any suitable cross-section, but is preferably made cylindrical and is also preferably formed or con-

structed of galvanized iron; but it may be of any suitable material.

B represents the bottom of the can, which, if preferred, may be so formed as to extend outward from the body, thus forming an annular flange b. The bottom B is secured to the body portion A in any suitable manner and, if desired, may be formed integral therewith.

C represents staves or cleats, preferably formed of wood and secured to the body by means of clips c c. These staves or cleats C serve to reinforce the body A of the receptacle and protect the same from indentation or injury during the hard usage to which these receptacles are subjected in handling and emptying the same.

D represents an annular trough which is located at and surrounds the upper portion of the body A. This trough D is made liquid-tight and is intended to receive or contain the liquid seal d. The liquid seal in this trough D may be water or may be a disinfectant consisting of some disinfectant or antiseptic substance mixed with the water. It will be noticed that the trough D extends outward from the body A of the receptacle approximately equidistant with the staves or cleats C. This is of more or less importance, inasmuch as it adds to the appearance of the receptacle, while at the same time the trough D is less liable to become injured while emptying the receptacle.

E represents the cover of the receptacle, which is provided with an annular flange e. The flange e is so formed and located as to be received in the trough D and is preferably so located as to fit loosely around the inner walls of said trough, thus keeping the cover from shifting. An annular horizontal flange e' may be provided, said flange extending out far enough to form a cover for the trough D. This prevents the evaporation of the liquid seal when the can is in exposed position—such, for instance, as in the sun.

F represents a valve which is located centrally in the cover E. This valve F, as illustrated more clearly in Fig. IV of the drawings, is composed of an outer casing F', provided with an annular seat f and a ball f', which fits against the seat f. A stem f² and

operating-handle F^2 are provided for operating the valve f' , which is done by depressing the handle F^2 for opening the valve and releasing it to allow the valve to close. A spiral spring F^3 is located around the stem f^2 and beneath the handle F^2 for automatically closing the said valve. The purpose of the valve F is to allow of the escape of the air when closing the receptacle, or, in other words, 5 when placing the cover in position, thus avoiding the forcing out of the water seal by over-due air-pressure when placing the cover. A handle G is located above the valve F in such 10 position that the said valve can be easily operated with the fingers of the same hand that manipulates the cover. The valve F is also used and employed in removing the cover E from the receptacle, thus allowing the cover 15 to be more easily removed without materially disturbing the liquid seal.

By constructing a can or receptacle of this character, as above set forth and according to my invention, I obtain a receptacle which is economical to construct, easy to operate or 20 cover, absolutely odorless when covered, and convenient to fill or empty, while at the same time all parts may be easily cleaned, inasmuch as there are no undercut portions, such as locks or the like.

25 While I have set forth in this specification and shown in the drawings my preferred method of constructing the body of the can and securing the sealing-trough thereto and also my preferred method of constructing the 30 valve in the cover of the can or receptacle, still I do not wish to be understood as limiting myself to these details, inasmuch as certain modifications may be made without departing from my invention.

35 40 What I claim is—

1. In a garbage-receptacle of the type set forth, the combination with a can having an external trough located at or near its top; an annular horizontal flange at its bottom extending beyond the body of the can, and cleats, fastened at intervals around the body 45

portion of the can, resting upon the bottom flange and fitting tightly under and supporting the external trough; of a cover provided with an annular depending flange adapted to enter the trough, and an annular horizontal flange adapted to extend over and cover said trough, substantially as and for the purpose set forth.

2. In a garbage-receptacle of the type set forth, the combination with a can having an external trough located at or near its top; an annular horizontal flange at its bottom extending beyond the body of the can, and cleats, fastened at intervals around the body 50 portion of the can, resting upon the bottom flange and fitting tightly under and supporting the external trough; of a cover provided with an annular depending flange adapted to enter the trough, and an annular horizontal 55 flange adapted to extend over and cover said trough, and having a handle; a vent-opening immediately under the handle, and a spring-actuated valve which normally closes the vent-opening, substantially as and for the 60 purpose set forth.

3. In a garbage-receptacle of the type set forth, the combination with a can, consisting of a cylindrical body portion A provided, at its lower end, with a bottom B , having an annular horizontal flange b , at its upper end with an external trough D , and with cleats C , fastened at intervals around the side, resting on the flange b and fitting under and supporting the trough D ; of a cover E provided 75 with an annular depending flange e , and an annular horizontal flange e' , and having a handle G ; a vent-opening located immediately under the handle and a spring-actuated valve F which normally closes said vent-opening, 80 substantially as and for the purpose set forth.

Signed by me at Cleveland, Ohio, this 27th day of August, 1898.

CHARLES J. VAUGHN.
